(57) **CLAIM**

The ornamental design for a one-piece guitar string cleaner, as shown and described.

DESCRIPTION

FIG. 1 is a top perspective view of a one-piece guitar string cleaner in the open position showing our design;

FIG. 2 is a top plan view thereof;

FIG. 3 is a front side elevational view thereof, the rear side being a mirror image thereto;

FIG. 4 is a bottom plan view thereof;

FIG. 5 is a left side elevational view thereof;

FIG. 6 is a right side elevational view thereof;

FIG. 7 is a bottom perspective view of a one-piece guitar string cleaner in the open position;

FIG. 8 is a bottom perspective view of a one-piece guitar cleaner in the closed position;

FIG. 9 is a top plan view thereof;

FIG. 10 is a front side elevational view thereof, the rear side being a mirror image thereto;

FIG. 11 is a bottom plan view thereof;

FIG. 12 is a left side elevational view thereof;

FIG. 13 is a right side elevational view thereof; and,

FIG. 14 is a top perspective view of a one-piece guitar string cleaner in the closed position.
